CENTRIFUGAL MACHINE

Wilmer H. Bath, West Conshohocken, Pa., assignor to The Sharples Specialty Company, Philadelphia, Pa., a corporation of Delaware

Application February 27, 1935, Serial No. 8,458

4 Claims. (Cl. 233—20)

The present invention relates to centrifugal separators designed to separate sludge from liquids, the term "sludge" as used herein being considered as designating not only impurities, but any materials including a large proportion of solids of higher specific gravity than the liquids in which they are suspended.

The invention relates more particularly to that type of centrifugal separators in which the solids are discharged through peripheral ports in the bowl structure and still more particularly to an improved means for closing such discharge ports.

In Nyrop application, Serial No. 700,687, filed December 2, 1933 and since eventuated into Patent No. 2,091,329, is shown a centrifugal separator of this type in which a circumferential piston is provided for sealing the outlet ports, and which is operated in accordance with the differential forces exerted by the liquid within the bowl and a liquid introduced to actuate the piston in one direction. I have found that with this structure, there has sometimes been a failure in the piston to completely uncover the ports, and as a consequence a detrimental amount of wire-drawing and erosion at the sealing edge of the piston has occurred. Furthermore, under some conditions of operation, the piston has failed to open quickly enough to effect a complete opening of the ports before the effective pressure within the separating bowl has been spent.

It is an object of this invention to overcome the difficulties and disadvantages above pointed out, and toward this end I have provided a hydraulically operated piston which is positively actuated in both directions of movement.

Another object of the invention consists in providing adequate packing means between the bowl structure and the reciprocating sealing piston.

Further and important objects will in part be evident as this description proceeds and will in part be more fully explained.

In this specification and in the annexed drawing, the invention is illustrated in what is now considered the preferred embodiment, but it is to be understood that the invention is not limited to the particular form shown, because it may be embodied in other forms and it is also to be understood that in and by the claims following the description, it is my desire to cover the invention in whatever form it may be embodied.

In the drawing, the single figure is a central axial sectional view illustrating one form the invention may take.

Referring to the drawing by reference characters, the shaft 11 of the machine may be driven

in any suitable manner, as for example, by a worm and worm-wheel drive. The upper end of the shaft 11 is secured within an opening in an upstanding boss 13 of the lower part 12 of the centrifugal bowl. The lower part of the bowl is conveniently made in two sections 12 and 14 which may be secured together in any suitable manner after the parts have been assembled. The lower part of the bowl is provided with an upstanding cylindrical wall 14 which is secured to an upper bowl member or cover 15 in any desired manner, such as by screws, these portions being secured together in spaced relationship in order to afford provision for a discharge opening 16 between the parts 12 and 15 of the bowl.

The interior of the bowl tapers from both ends toward the middle and has a maximum interior diameter at the zone of junction between a gasket 28 and a piston 27 in the neighborhood of the discharge opening 16. A central distributing feed tube 17 is secured to the bowl in such a position as to feed the material to be treated into the bottom portion of the bowl and a suitable disc inset 18 is also secured within the bowl, the disc inset and distributing tube being secured in place by means of a nut 19 which is threaded on the upper outer circumference of the distributing tube.

Accelerating wings 24 are provided and these wings can be fixed to rings 25 in order to facilitate their removal for cleaning. A skimming plate 20 directs the lighter effluent separated from the liquid within the bowl to a discharge outlet 23 and a heavier effluent through openings 22 under the control of an interchangeable weir 21.

The bowl members 12 and 14 are circumferentially spaced in order to provide therebetween a groove in which a piston 26 may reciprocate. The piston 26 is provided with an upstanding body member 27 which is adapted to contact a sealing gasket 28 in the upper bowl member 15. The lower end of the piston 26 has an inwardly projecting boss 29 which is loosely engaged by a circumferential ring 30 which is adapted to move in a recess 31. Piston 26 is provided with ports 32 spaced at intervals about its circumference and in communication with a circumferential groove 33 on the inner face of the piston 26. When the piston 26 abuts gasket 28 to close the circumferential discharge port 16, port 32 registers with an opening 34 in the lower bowl member 14. The ring 30 is positioned within the lower bowl member to provide a certain amount of clearance 35 between the same and the bowl member 12 for a

purpose which will hereinafter be described.

Part 14 of the lower bowl is provided with a neck 36 which has therein circumferential grooves 37 and 38. Groove 37 communicates 5 with a duct 39 which in turn opens into the circumferential chamber 31 beneath the piston and member 30. Groove 38 communicates by means of a duct 40 with a second duct 41 communicating with the space 35 between the ring 30 and 10 the inner bowl member 12. Jets 42 and 43 are provided to direct water or other liquid into the grooves 37 and 38 respectively for a purpose which will hereinafter be more fully described.

In order to provide a tight seal between the 15 bowl member 12 and the piston 26, I have provided a packing member of peculiar construction located in a circumferential groove in the inner bowl member 12. In the packing member, 44 and 20 45 represent circumferential flanged rings which are held in position and in spaced relation by a spacer ring 46, between a shoulder in the circumferential groove and a retaining ring 12' which is affixed to the bowl member 12 in any suitable manner after the packing member has been 25 placed in position. To the rear of the flanged ring 44, which is made of flexible metal, is fixed a lead weight 47 which performs the function of forcing the vertical portion of ring 44 into tight engagement with the piston 26 under the influence 30 of centrifugal force. I have found that a metal to metal seal is not entirely satisfactory under all conditions of operation, and for this reason, I have modified the sealing effect of the ring 45 by attaching thereto a band of fabric material 48 35 which is held between the vertical portion of the flanged ring 45 and a lead strap 49 which is suitably attached to the ring 45. With this arrangement, I have been able to secure a very satisfactory seal under widely varying conditions of 40 operation. The extension 50 of the circumferential groove in member 12 may ordinarily be filled with a plastic sealing material, such as, for instance, graphite.

In order to prevent liquid from passing between 45 the piston 26 and the bowl member 14, I have provided a packing ring 51 which extends into contact with the piston 26 and which is held in place in a circumferential groove in the base of member 14 by means of a retaining ring 52.

In the normal operation of the machine, let it 50 be assumed that the piston 26 has been closed by means of liquid from jet 42 which by centrifugal force is led to the duct 39, into the chamber 31 and under the lower end of the piston 26 where a 55 considerable hydraulic pressure is developed. An open outlet 53 limits the extent to which liquid is retained in the chamber 31 and this limit extends to the inner edge of the boss 29. Now, with the piston 26 in its upper position and in tight contact with the gasket 28, the material to be treated 60 may be fed into the distributing tube 17 and the separator may be operated until a considerable portion of sludge has collected at the zone defined by the outer circumferential edges of the bowl 65 member 12 and 15. If it now becomes desirable to open outlet port 16, the piston 26 may be quickly and positively actuated by admitting liquid from the jet 43 to the groove 38 into the channel 40 and from there through the channel 70 41 to the clearance space 35. Centrifugal force causes a considerable hydraulic pressure to develop above the member 30 and since the area against which this hydraulic pressure operates is greater than the area of the lower end of the piston 26, the pressure within the outer edge of

chamber 31 is quickly overcome and the piston 26 is immediately lowered, liquid from the chamber 31 being discharged through the outlet 53. Inasmuch as the lower end of the piston 26 and the ring 30 are only in loose engagement, liquid 5 from the space 35 quickly finds its way over the ring 30, into the circumferential groove 33 in piston 26 and through the discharge ports 32 and 34. Thus, the closure mechanism is quickly prepared for another cycle of operation, for when the liquid supply from the jet 43 is cut off and liquid from the jet 42 is supplied, pressure again quickly develops under the lower end of the piston 26 and carries the same upwardly into closed position and with it member 30. 10 15

Having thus described my invention, what I claim and desire to secure by Letters Patent is:

1. A centrifugal separator adapted to be rotated to effect the continuous discharge of a liquid effluent during the concentration of suspended 20 solid material within the bowl, said separator including a cover and a base having a discharge passage therebetween, the base thereof comprising an annular outer casing member and an inner sludge supporting member spaced therefrom to form a 25 narrow sealing piston chamber therebetween to receive such piston and support the same throughout substantially its entire length, an enlarged chamber at the bottom of the said sealing piston chamber, a piston mounted within the bowl for reciprocation within said chamber, a sealing member within said bowl and beyond said chamber adapted to be abutted by one end of said piston in one position to prevent the undesired discharge 30 of sludge through the discharge passage, a radial flange projecting inwardly from said piston and into said enlarged chamber, means for admitting liquid to a space above said radial flange for moving said piston into sludge discharging position, and means for admitting liquid under said 35 piston for moving said piston to sludge retaining position. 40

2. A centrifugal separator adapted to be rotated to effect the continuous discharge of a liquid effluent during the concentration of suspended 45 solid material within the bowl, said separator including a cover and a base having a discharge passage therebetween, the base thereof comprising an annular outer casing member and an inner sludge supporting member spaced therefrom to form a narrow annular sealing piston chamber therebetween to receive such piston and support the same throughout substantially its entire 50 length, an enlarged chamber at the bottom of the said sealing piston chamber, an annular piston mounted within the bowl for reciprocation within said chamber, a sealing member within said bowl and beyond said chamber adapted to be abutted by one end of said piston in one position to prevent the undesired discharge of sludge through the discharge passage, a radial flange 55 projecting inwardly from said piston and into said enlarged chamber, means for admitting liquid to a space above said radial flange for moving said piston into sludge discharging position, and means for admitting liquid under said piston for moving said piston to sludge retaining position. 60

3. A centrifugal separator adapted to be rotated to effect the continuous discharge of a liquid effluent during the concentration of suspended 70 solid material within the bowl, said separator including a cover and a base having a discharge passage therebetween, the base thereof comprising an annular outer casing member and an inner 75

sludge supporting member spaced therefrom to form a narrow sealing piston chamber therebetween to receive such piston and support the same throughout substantially its entire length, an enlarged chamber at the bottom of the said sealing piston chamber, a piston mounted within the bowl for reciprocation within said chamber, a sealing member within said bowl and beyond said chamber adapted to be abutted by one end of 5 said piston in one position to prevent the undesired discharge of sludge through the discharge passage, a radial flange projecting inwardly from said piston and into said enlarged chamber and having operating contact with said piston for 10 moving the same into sludge discharging position only, means for admitting liquid to a space above said radial flange for moving said piston into sludge discharging position, and means for admitting liquid under said piston for moving said 15 piston to sludge retaining position.

4. A centrifugal separator adapted to be rotated to effect the continuous discharge of a liquid effluent during the concentration of suspended solid material within the bowl, said separator including a cover and a base having a discharge 20

25

passage therebetween, the base thereof comprising an annular outer casing member and an inner sludge supporting member spaced therefrom to form a narrow annular sealing piston chamber therebetween to receive such piston and support the same throughout substantially its entire length, an enlarged chamber at the bottom of said sealing piston chamber, an annular piston mounted within the bowl for reciprocation within said chamber, a sealing member within 5 said bowl and beyond said chamber adapted to be abutted by one end of said piston in one position to prevent the undesired discharge of sludge through the discharge passage, a radial flange projecting inwardly from said piston and 10 into said enlarged chamber and having operative contact with said piston for moving the same into sludge discharging position only, a liquid head limiting port in said bowl at the inner radius of said piston, means for admitting liquid to a 15 space above said radial flange for moving said piston into sludge discharging position and means for admitting liquid under said piston for moving said piston to sludge retaining position.
